UNITED STATES PATENT OFFICE.

STEPHEN W. GOODYEAR AND MARION A. MORRIS, OF WATERBURY, CONN.

ROTARY WIRE-STRAIGHTENER.

SPECIFICATION forming part of Letters Patent No. 277,267, dated May 8, 1883.

Application filed March 6, 1883. (No model.)

To all whom it may concern:

Be it known that we, STEPHEN W. GOOD-
YEAR and MARION A. MORRIS, citizens of
the United States, residing at Waterbury, in
5 the county of New Haven and State of Con-
necticut, have invented certain new and use-
ful Improvements in Rotary Wire-Straighten-
ers; and we do hereby declare the following
10 to be a full, clear, and exact description of the
invention, such as will enable others skilled
in the art to which it appertains to make and
use the same.

Our invention relates to the class of machines
for straightening wire in which the wire is
15 passed longitudinally through a succession of
holes or dies, or between concave bearing-points
ranged at intervals in a frame which is mounted
in bearings and rapidly revolved, the said
succession of holes or bearing-points being ad-
20 justable in a direction transverse to the axis
of the revolving frame; and the objects of our
invention are, first, to prevent the spiral
marks on the surface of round wire or metal
bars which result from straightening them in
25 the rotary straighteners now in use; second,
to make it possible to straighten tubing of so
light a character that it would be twisted or
crushed by any attempt to straighten it in an
ordinary straightener; third, to provide means
30 for straightening wire or bars of metal of other
shapes than round, which have been hitherto
imperfectly straightened in what are known
as "roll-straighteners," as an attempt to
straighten them in any rotary straightener now
35 in use would result in wearing off the corners
of the wire or bar, and would soon cut out and
wear away the friction-surfaces of the pins or
dies which come in contact with the wire as
the straightener is revolved. In practice, in
40 the rotary straightener now in use, the wire
is passed through a succession of holes or dies,
or between concave bearing-points adjustably
arranged in a frame which is so mounted as to
permit of rapid rotation, the holes or bearing-
45 points being so adjusted that the wire in pass-
ing through the straightener is forced out of
line with the axis of the revolving frame in all
directions, each part of the wire as it is drawn
through being subjected to this deflecting in-
50 fluence, causing it to pass through the straight-
ener in a serpentine course, emerging there-
from in a practically straight condition, but

with very objectionable spiral marks produced
by the rotating friction-surfaces of the holes or
bearings in the pins or dies through which it 55
has been passed.

Our invention consists in the use of non-
rotating shells or thimbles through which the
wire passes, and which are interposed between
the rotary friction-surfaces, which would other-
wise come in direct contact with the wire, and
60 the wires themselves. The non-rotating shells
or thimbles take upon themselves the rotary
friction which has heretofore been brought to
bear directly upon the surface of the bar or 65
wire, the result being a surface free from marks
such as are made by the rotary straightener
now in use.

In order to enable those skilled in the art
to which our invention appertains to make and
use our improvement, we will proceed to de-
75 scribe the same, referring by letters to the ac-
companying drawings, forming part of this
specification, in which—

Figure 1 is a side elevation of a wire-straight- 75
ening machine embodying our invention, the
non-rotating thimbles being loosely held be-
tween the ends of screw-threaded pins which
pass through the revolving frame from the out-
side, said pins being securely held from move- 80
ment by check-nuts upon their outer ends.
Figs. 2 and 3 are top and side views of a por-
tion of the frame, with the pins made smooth
and held in place by set-screws. Fig. 4 is a
85 detail view of one of the pins, the inner end
being in section to show the socket, and also
a pin in the base of the socket, for a purpose
presently to be described. Fig. 5 is a section
of one of the shells or thimbles.

Similar letters of reference denote like parts 90
in all the figures of the drawings.

It is not deemed necessary to minutely de-
scribe the machine itself, as it has long been in
common use and is not of our invention, and,
moreover, our invention is adapted for use in 95
any form of rotary straightener.

A is the base of the machine, and B B the
standards, having bearings B' B', which sup-
port the revolving frame C.

D D' are fast and loose pulleys. One of them, 100
being rigidly attached to the trunnion of frame
C, imparts motion thereto.

E is a bracket-arm having an aperture, K,
which may hold a shell having an aperture

similar in shape and size to those in the shells in the revolving frame, and which serves to guide the wire as it leaves the machine. A similar aperture, I, may be provided for the wire to pass through as it enters the machine.

Both sides of the revolving frame are provided with holes *c c*, preferably screw-threaded, through which are passed a series of correspondingly screw-threaded pins or bolts, F. F. 10 The inner ends of these pins are provided with sockets *f*, and between the ends of each pair of pins, and resting in the sockets, is loosely held a perforated shell or thimble, G. The pins or bolts F are preferably held against displacement by check-nuts H, as shown in Fig. 15. If preferred, however, the pins may be made smooth, as shown in Figs. 2 and 3, and held in place by set-screws in the frame.

We also contemplate placing pins, as *f'*, in 20 the bottoms of the sockets *f*, which are adapted to engage with a circular groove around the periphery of the shells or thimbles, thereby preventing a swiveling or oscillating motion of the latter transverse to the axis of the shells 25 to such an extent as would keep the holes in the shells near enough in line with each other, so that the wire may be readily inserted.

It will of course be understood that it is not essential that the shells or thimbles be made in 30 the form of spheres, as a conical or cylindrical form may be adopted without departing from the spirit of our invention, it being only necessary in carrying out our improvement that the outer circumference of the shells or thimbles 35 be of some suitable shape to form a bearing-surface for the screws or pins, which by revolving around in contact with the shells or thimbles cause the thimbles which are out of line with the axis of the rotary frame to have 40 a motion in a circle around said axis without rotating them on their own axes, so that the desired effect of straightening the wire is accomplished without the slightest injury to the surface thereof. The use of non-rotating shells 45 or thimbles removes the great objection to straightening round wire and light tubing in rotary straighteners. The rotary straighteners now in use, moreover, can only be used for round wire; but our improved machine is 50 equally adapted for straightening square, angular, half-round, or any other style of wire, tubing, or bars, it being only necessary to provide shells or thimbles having perforations corresponding in size and shape with the wire 55 or bars to be straightened.

In using our invention for wire, bars, or tubes of other shapes than round it is desirable to pass it through a stationary aperture of the same shape and size as the apertures 60 in the series of thimbles through which it is

to pass, either as it enters or as it leaves the machine, or, if preferred, at both points.

In use the shells or thimbles are ordinarily adjusted as follows: Any number of shells may be used from three upward; but five 65 will be found a suitable number for ordinary purposes, the first being centered with the wire or bar as it enters the machine, the second slightly out of line to the left, the third out of line to the right, the fourth to the left, 70 and the fifth centered with the first, and with the stationary apertures should one or both be used. As soon as the wire has been started in the machine the frame is rapidly rotated, which causes each portion of the wire, as it 75 passes through, to be deflected or bent in all directions, but without twisting and without any rotary friction on the surface of the wire, so that the latter, when it emerges, will be thoroughly straightened, but will be wholly 80 free from objectional marks.

What we claim as our invention, and desire to secure by Letters Patent, is—

1. In a wire-straightener, a series of non-rotating independent thimbles capable of lateral adjustment by means of pins secured within the rotary frame, the shells, when the machine is in operation, having no axial rotation, but a movement in a circle around the axis of the rotary frame, substantially as set forth 90 and described.

2. The combination, with the rotating frame and adjustable pins or bolts; of the shells or thimbles held in operative position by said pins or bolts, substantially as shown and de- 95 scribed.

3. The combination, with the rotating frame, screw-threaded pins or bolts held in place by check-nuts, as shown, of non-rotating shells or thimbles loosely held in position between 100 the ends of the pins which are turned in from opposite sides of the frame, as set forth.

4. The combination, in a machine for straightening wire, of the frame C, pins or bolts F, shells G, and a stationary aperture at one or both ends of the machine, substantially as 105 specified.

5. The combination, with the frame rotating in standards, as shown, and the pins F, having sockets *f* and pins *f'* at their inner ends, 110 of the shells G, having grooves in their peripheries, with which pins *f'* engage, for the purpose set forth.

In testimony whereof we affix our signatures in presence of two witnesses.

STEPHEN W. GOODYEAR.
MARION A. MORRIS.
